UNITED STATES PATENT OFFICE.

ARTHUR F. POOLE, OF KENILWORTH, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

TOTALIZER CLEAR SIGNAL.

1,426,502.

Specification of Letters Patent. Patented Aug. 22, 1922.

Application filed November 17, 1919. Serial No. 338,442.

To all whom it may concern:

Be it known that I, ARTHUR F. POOLE, a citizen of the United States, residing at Kenilworth, in the county of Cook and State of Illinois, have invented certain new and useful Improvements in Totalizer Clear Signals, of which the following is a specification.

My invention is a calculating machine and has particular relation to a total clear signal for the purpose of insuring that the correct total shall be extracted from the machine.

My invention is shown as applied to the well-known Wahl machine now extensively marketed by the Remington Typewriter Company and the structure of which is described in numerous issued patents, particularly the patent to Wahl, No. 893,719, dated July 21, 1908, supplemented by the disclosure of the patent to Wahl, No. 1,270,471, dated June 25, 1918.

In the Wahl machine, which is a type-writing adding machine, there is present a typewriter which is adapted to write both letters and numerals, the typewriter being provided with the customary platen and ribbon mechanisms. On the front part of the typewriter is mounted what is called an actuator, and this actuator is connected to the numeral keys of the typewriter. The function of the actuator is to translate the vertical reciprocation of the typewriter numeral keys into a differential rotation of a wheel called the master wheel. The direction of rotation of the master wheel is controlled by a gear-shifting mechanism, so that the wheel may rotate either in a direction determining addition or in a direction determining subtraction upon the operation of the typewriter numeral keys.

Also mounted on the front of the typewriter is a truck sliding in bearings and suitably connected to the typewriter carriage so as to advance step by step with said carriage. A series of two or more totalizers are mounted on the truck and the master wheel serves to insert numbers in these totalizers one digit at a time. To insert a number, the truck is tabulated by means of the tabulator keys customarily present in a Remington typewriter to the decimal place corresponding to the extreme left end digit of the number desired to be inserted. The numeral key corresponding to this digit is

then pressed, with the result that the master wheel rotates a number of steps, corresponding to said digit, and inserts the digit into the totalizer, the direction of rotation of the master wheel being determined by the position of a gear shifting mechanism. After the insertion of the first digit the typewriter carriage escapes one step, carrying with it the truck and its thereon mounted totalizers. The mechanism is now in position for the reception of the second digit of the number. The numeral key corresponding to this digit is operated, resulting in the inserting of the second digit into the totalizer. Numbers are inserted into the totalizer in this manner digit by digit until the entire number has been inserted. The paper is then line spaced and the mechanism is ready for the reception of a new number.

The Wahl machine has no means for automatically printing out the total. When one wishes to print out a total appearing in one of the totalizers, the gear shifting mechanism is put into a position determining subtraction, the carriage is tabulated so that the master wheel is in mesh with the totalizer at the first significant digit and the numeral keys are operated in the succession shown by the number exhibited in the totalizer, the carriage spacing one step to the left after the operation of each key. This results in the subtracting of the exhibited total from the totalizer which returns to zero, and also in printing said total on the work sheet.

While extracting a total in the manner just described, it sometimes happens that an operator misreads the figure appearing in the totalizer, and in consequence thereof operates the wrong digit key. This results in the totalizer being left with a number still in it, instead of being wholly clear. If the error is not noticed and a new computation commenced, the new computation will, of course, be in error by the number left in the totalizer. This will result in two erroneous computations, the one in which the total was erroneously extracted and the new computation which started with the totalizer not clear.

My herein described invention has for one of its objects the forestalling or rendering impossible the erroneous manipulation just

described, and to this end I have provided a special key which is provided with a characteristic type, such as a star. This star is always printed to the right of an extracted total. In the event that the totalizer is not clear at the time it is attempted to print this star, then the star key cannot be put through its complete cycle, but will be locked up. The attention of the operator will be called to the mistake by the fact of its being impossible to further operate the calculating machine; the mistake will then be rectified and the correct total written out.

Another object of my invention is to so interlock the star printing key with the other mechanism that said key cannot be operated, except to print a star at the right of a total which has been extracted from the machine.

Another object of my invention is to provide mechanism in the totalizer cooperating with mechanism in the actuator, to the end that when an attempt is made to operate the star printing key without the total being completely extracted from the totalizer, this star printing key will be held in its depressed position.

Another object of my invention is to combine the 9 test described in my issued Patent No. 1,283,293, patented October 29, 1918, with the mechanism for holding the star printing key in its depressed position in the event that one attempts to print a star after a number which is not the correct total of the numbers entered into the totalizer; in other words, if one attempts to print this star when the totalizer is not clear, thus providing a double safe-guard.

The above and other objects of my invention will be apparent to those skilled in the art from a reading of the following specification and claims:

My invention may be best understood by reference to the following figures of drawings, of which—

Fig. 1 is a front view of a typewriting and calculating machine equipped with my improved device;

Fig. 2 is a back view of the adding mechanism;

Fig. 3 is a perspective view of the parts peculiar to my present invention;

Fig. 4 is a section along the lines 4—4 of Fig. 1;

Fig. 5 is a section along the lines 5—5 of Fig. 1;

Fig. 6 is a front view of the mechanism shown in Fig. 5;

Fig. 7 is a section of the cross actuator and totalizer on the line 7—7 of Fig. 1;

Fig. 8 is a perspective view of a modified form of my invention.

Referring particularly to Figs. 1 and 4, the typewriter 10 is provided with ten

numeral keys, Nos. 11 to 20 inclusive, the last key 20 being the key associated with the zero, this key printing 0, but not inserting any number into the totalizer, the action of the key serving simply to space the typewriter and actuate certain universal members in the actuator, such as the full stroke pawls and the master dog to be hereinafter described.

Each of the numeral keys is connected by a pull rod 21 to fans 22 in the actuator, which fans may be identified as the fans 71 in Fig. 14 of the cited patent to Wahl, No. 1,270,471. The fans 22 are rotatably mounted on a fixed rod 23, and each of them except that connected with the zero key serves to actuate a gooseneck 24, which serves to give a differential rotation to a sector shaft 25 mounted in the framework of the machine. The differential rotation of the sector shaft 25 ultimately results in the differential rotation of a master wheel 26. It will not be necessary to trace the chain of mechanism between the sector shaft 25 and the master wheel 26, since this mechanism has been thoroughly described in said patent to Wahl, No. 1,270,471, to which reference may be had for a detailed description of the operation.

There is a fan 22 associated with each of the pull rods 11 to 20 inclusive, and, as thoroughly described in the cited patent to Wahl, No. 1,270,471, motion of any of the numeral keys results in differential rotation of the master wheel.

The vertical totalizers 27, 28, 29 and 30 are mounted on a truck 31, which is connected to the typewriter carriage (not shown), and advances synchronously with said carriage, thus bringing successive totalizers into cooperation with the master wheel 26. There is also provided a cross totalizer 32, which is adapted to be picked up and reciprocated by the vertical totalizers 27 to 30 inclusive during the travel of the carriage. The cross totalizer will thus add numbers written in a horizontal line, and, simultaneously, each of the vertical totalizers 27 to 30 inclusive will accumulate the numbers as written in a column. It will not be necessary to describe the mechanism by which the cross totalizer is reciprocated, since this mechanism is also very thoroughly described in the cited patent to Wahl, No. 1,270,471.

The cross totalizer is actuated by the cross actuator 33 having a cross master wheel 34. The cross actuator 33 is connected to the main actuator 35 by a pair of links 36, but one of which is shown in my present application, the complete mechanism being fully shown in the cited patent to Wahl, No. 1,270,471, in which the links are numbered 164 and 167 (Fig. 4, Sheet 3). The main actuator 35 is provided with a rockshaft 37, 130

which shaft is actuated on the downstroke of any of the numeral keys by a cam 38 on the fan 22 engaging a universal bar consisting of a roller 39 mounted on crank arms 40 rigid with the rockshaft 37. The parallelogram linkage between the rockshaft 37 of the upper actuator and a similar rockshaft 38' mounted in the cross actuator 33 serves to give the cross rockshaft 38' exactly the same motion as that given to the rockshaft 37 in the main actuator 35. By means of this parallelogram linkage just described the calculating parts in the cross actuator 33 are given movements concurrent with the movements of the calculating parts in the vertical actuator 35. It will not be necessary to trace in detail the mechanisms by which this result is accomplished, since this mechanism is also thoroughly described in the cited 20 patent to Wahl, No. 1,270,471.

The vertical master wheel 26 is provided with a gear control consisting of mechanism whose position is governed by the vertical control handle 39, the position of said handle determining that the vertical master wheel 26 shall operate its then associated totalizer either in addition, subtraction or disconnect.

The cross master wheel 34 is adapted to be controlled from either of two sources, one of these is a manual control operated by the handle 40, and the other is an automatic control operated by cams 41, 42 and 43, mounted respectively on the vertical 35 totalizers 27, 28 and 30. It is not necessary to trace out the mechanism by which these cams 41, 42 and 43 and the handle 40 control the cross master wheel 34, since the mechanism is like that described in the cited patent 40 to Wahl, 1,270,471, for performing a similar function. It will be sufficient to note that the master wheel 34 may be either in addition, subtraction or disconnect, as determined by the position of the handle 40, and that it also may be in either addition, subtraction or disconnect, as determined by one of the cams 41, 42 or 43 or by the absence of any such cam. A control shift handle 44, by its position, determines whether the position 45 of the handle 40 shall be effective to control the state of the master wheel 34, or whether the state of said wheel shall be determined by the automatic control consisting in part of the cams 41, 42 and 43.

55 In addition to the gear controls above described, the Wahl machine is also provided with a universal correcting lever 45. The function of this lever is to throw both the vertical master wheel 26 and the cross master wheel 34 into the reverse of their conditions, as determined by the position of the other gear controlling mechanism on the machine. This is for the purpose of correcting an erroneous insertion in the totalizer. The 60 mechanism constituting the gear controls

just described is the same as that shown in the cited patent to Wahl, No. 1,270,471, and since this gear control mechanism has been thoroughly described in said patent, it will not be necessary to repeat the description in 70 this place.

I shall now describe the mechanism peculiar to my present invention. This mechanism can be best understood by reference to Fig. 3, which is a perspective view of the 75 parts peculiar to my present invention.

In Fig. 3 I have shown my invention as applied to the cross totalizer of a Wahl machine. The mechanism may be divided into two parts, which will be described separately, although both of these parts cooperate to the common end of preventing the operation of the star key unless the cross totalizer stands at clear. One of these parts is a function computing device similar in 80 theory to the device described in my issued patent No. 1,283,293, dated October 29, 1918, and adapted to compute the 9-function of the numbers entered into the totalizer. The purpose of this mechanism may be briefly 85 stated here-to be the prevention of the operation of the star printing key except the totalizer stands at zero or at a multiple of 9.

The theory of the mechanism need not be given in this place, since it is thoroughly described in my Patent No. 1,283,293, just referred to. For the purpose of the present disclosure it will be sufficient to note that the cross master wheel 34 is mounted on a shaft 46 rotatably mounted in the framework of the machine. Mounted on the shaft 46 is a gear 47 having the same number of teeth as the cross master wheel 34. The shaft 48 is rotatably mounted in the framework of the cross actuator and has 100 mounted on it a gear 49 having 27 teeth, said teeth meshing with the gear 47.

Rigidly mounted on the shaft 48 is a control cam 50 having three notches 51, 52, and 53 therein, these notches being spaced 120° apart. An indicator lever 54 is pivoted in the framework on a shaft 55 and has a nose 56 adapted to enter any of the notches 51, 52, or 53. The indicator lever 54 is held in contact with the cam 50 by means of a spring 57 extending between the lever 54 and a stud 58 mounted in the framework of the cross actuator. The indicator lever 54 is provided with a pointer 59, which when the nose 56 is in registry with any of the notches 51, 52 or 53 stands opposite an indicator mark 60 on the casing of the cross actuator.

Mounted on a shaft 61, rotatably mounted in the cross actuator, is a bell crank 62 having a nose 63 adapted to register with the notches 51, 52 and 53. The lever 62 is connected by a link 64 with a lever 65 pivoted at 66 in the cross actuator and engaging by a pin and slot connection 69 with a lever 67 130

pivoted on the cross actuator at 68. The lever 68 is joined by a pull rod 70 to the star printing key 71.

In Fig. 3 I have shown the mechanism just described displaced from its normal position in order to clearly show the chain of mechanism between the cam 50 and the key 71. In Fig. 3 the pull rod 70 is numbered both at its connection with the lever 67 and 10 at its connection with the key 71. In the machine these two portions are coincident, although in the drawing in Fig. 3 they are shown separated.

From the above it is evident that when any 15 of the notches 51, 52 or 53 is in registry with the nose 63, then the star printing key 71 may be operated. If, however, the nose 63 is resting on the concentric surface of the 20 cam 50, then the star printing key cannot be operated.

From the theory of the operation of the mechanism just described, as given in my cited Patent No. 1,283,293, it will be evident that if the position of the cam 50, as shown 25 in Fig. 3, is coincident with the cross totalizer standing at zero and then a series of numbers are inserted into the cross totalizer, coincidence of the notches 51, 52 or 53 with the nose 63 will not occur, unless the totalizer stands either at zero or at some multiple 30 of 9. Accordingly, if at the beginning of a computation the disc 50 is set so that the nose 63 coincides with one of the notches 51, 52 or 53, then it will not be possible to print 35 the star key unless the cross totalizer stands either at zero or some multiple of 9, viz., 9, 99, 198, etc.

This condition will obtain regardless of 40 whether numbers are inserted into the totalizer in addition or in subtraction. Consequently if a series of numbers are added into the cross totalizer and then the total of these numbers is subtracted out, the totalizer should stand at zero and the operation of 45 the star key 71 will be permitted. However, if the total has not been completely extracted, the operation of the star printing key 71 will not be permitted unless it so happens that the number left in the totalizer 50 is some multiple of 9. It is therefore desirable to combine the 9 test mechanism just described with an additional mechanism which will insure the attention of the operator being directed to the case in which the 9 test 55 will give an incorrect result, that is, the case in which the number standing in the totalizer after a clearing operation is some multiple of 9.

To take care of this latter case, I have provided 60 the cross totalizer 32 with a mechanism which, in the event the star printing key is operated when the totalizer does not stand at zero, will prevent the star printing key 71 from returning to its normal position and thus the attention of the operator

will be called to the fact that an incorrect total has been subtracted from the totalizer. This latter mechanism will now be described.

The cross totalizer 32 is provided with a set of number wheels 72 which are visible 70 through a window 73 (Fig. 7) in the casing 74 of the totalizer 32. Rigid with each of the number wheels 72 is a gear 75, by means of which the number wheels are driven from the gears 76 in the totalizer. The cross totalizer 75 is in the main exactly like the cross totalizer described in the cited patent to Wahl, No. 1,270,471, and the mechanism of this totalizer and its operation need not be further described herein.

Each of the gears 75 is provided with a short tooth 77, by means of which the zero position of the number wheels 72 may be determined.

Rotatably mounted in the framework of 85 the totalizer is a shaft 78 having a series of comb teeth 79 thereon, there being one of these teeth for each number wheel of the totalizer. The comb teeth 79 are in the plane of the gears 75, and are urged into 90 contact with said gears by a spring 80, which urges an arm 81 rigid with the comb teeth 79 to rotate in a counterclockwise direction (Fig. 3). However, the teeth 79 will be in the position shown in Fig. 3, except the totalizer stands at zero, in which event all of the short teeth 77 will be opposite the cooperating tooth 79 and said teeth will rotate under the influence of the spring 80. When the arm 81 rotates, it actuates 100 a latch 82 rotatably mounted on a stud 83 in the side plate of the totalizer 32. A spring 84, extending between the latch 82 and a stud 85 in the framework tends to hold the latch 82 in the position shown in 105 Fig. 3.

A bell crank lever is rotatably mounted on a cross shaft 87 in the totalizer side plates, and a spring 88 extending between the lever 86 and a stud 89' in the totalizer side plate 110 tends to give the lever 86 a tendency to rotate in a counter-clockwise direction (Fig. 3). The lever 86 has a fork in its lower end having prongs 89 and 90, these prongs being in a position to be engaged by the 115 master dog 91 customarily present in the Wahl machine, and whose action is fully explained in the description of the dog 123, page 5 lines 16 to 70 of the cited patent to Wahl No. 1,270,471. The prongs 89 and 120 90 of the fork are, as before noted, adapted to be engaged by the master dog when the totalizer is one space to the left of the lowest decimal place, which place I shall hereinafter call the sub-units place of the totalizer. The star printing key 71 is attached by a pull rod to a special fan 93 in the vertical actuator. Consequently when the key 71 is operated, there will result motion 125 of the cross master dog 91, which will raise 130

the lever 86 from its normal position, as shown in Fig. 7, to its position as shown in Fig. 3. If now there is a number present in the totalizer, the latch 82 will be in the position shown in Fig. 3. Consequently, the lever 86 will be held in its upper position, and upon the attempted return of the master dog the prong 90 of the fork will prevent the master dog from returning to its 10 normal position.

I shall now explain how prevention of return of the master dog to its normal position will lock the star key 71 in its depressed position. The Wahl machine is provided 15 with what is known as a full stroke mechanism. This consists of the pawls 94 and 95, which are adapted to engage teeth 96 and 97 present on all of the fans. It will be remembered that on the downstroke of the 20 key in the Wahl machine the rockshaft 37 is thrown to the position shown in Fig. 3. An arm 98 is rigid with the rockshaft, and, by engaging an arm 99 rigid with the front fullstroke pawl 95, holds this pawl out of 25 engagement with the teeth 97, thus permitting the downstroke of the key. However, the back fullstroke pawl 94 is held by a spring 100 connected between the fullstroke pawls 95 and 94 into engagement with the 30 teeth 96.

It is explained in the cited patent to Wahl, No. 1,270,471, how, on the upstroke of the key the rockshaft 37 is thrown to a rear position and when in said position a lever 101 rigid with the back fullstroke pawl 94 is engaged by the arm 98 and said pawl lifted out of engagement with the teeth 96, thereby permitting the upstroke of the key. It will be evident that if by 40 any means the return of the rockshaft to its normal position is prevented, then the back fullstroke pawl 94 will not be lifted from its engagement with the teeth 96 and therefore the return stroke of the key 71 will be prevented. It has been pointed out 45 before herein that the rockshaft 37 of the vertical actuator is connected to the cross rockshaft 38' by the parallelogram link 36. The cross rockshaft 38' has mounted rigidly 50 upon it a crank arm which is connected by a link 103 with a cam plate 104 engaging with a roller 105 on the master dog 91. Rotation of the rockshaft 38, by means of the cam plate 104 thus rocks the master dog 55 91 from its normal position as shown in Fig. 7 into its displaced position, as shown in Fig. 3. Consequently, if the master dog 98 is prevented from returning to its normal position by the prong 90, then the return 60 of the cross rockshaft 38 to its normal position will be prevented and in consequence return of the vertical rockshaft 37 will be prevented. This will prevent the changing of the fullstroke pawls from the rear 65 pawl 94 to the front pawl 95, and the rear

pawl 94 will remain in engagement with the teeth 96. Upward motion of the key 71 will, therefore, be prevented.

From the preceding it is apparent that if the star key 71 is operated at a time the 70 totalizer does not stand at zero, then the key 71 will not be able to complete its stroke and will be held in its depressed position. If, however, the key 71 be operated when the totalizer 32 stands at zero, 75 then, because the short teeth 77 are opposite the teeth 79, the arm 81 may rotate slightly under the influence of the spring 80 and thus hold the latch 82 out of a position to engage the lever 86. Said lever will then 80 return to its normal position upon the upstroke of the key, and thus the star printing key may perform a complete stroke without interference.

It is to be noted that the cam 50 will 85 prevent the operation of the key 71, except when the totalizer stands at zero or a multiple of 9, such as 99, 198, etc. However, if the totalizer 32 stands at a multiple of 9 other than zero and it is attempted to operate the 90 key 71, then said key will not be able to go through a complete stroke, but will be held at the bottom of its downstroke and the attention of the operator will be called to the fact that the key 71 has been operated 95 without the totalizer being clear.

In order to release the mechanism after a misoperation of the key 71, I have provided the latch 82 with a fingerpiece 105' which projects through the side plate of the totalizer and by which the latch 82 may be operated when the key 71 is held in its bottom position as just described, then by means of the fingerpiece 105' the latch 82 is pulled out of engagement with the lever 105 86. This will permit the return of the star printing key 71. The totalizer is then corrected, that is, the number standing in the totalizer is subtracted out, and when this is done the star key 71 may be operated a complete stroke without interference.

It is desirable that the star printing key be so interlocked with the numeral keys that it is possible to operate the star printing key only in the sub-units place of the totalizer. To this end I have provided the vertical totalizer 30 with a cam 106 adapted to engage a roller 107 mounted on a crank arm 108 rigid to a shaft 109 rotatably mounted in the framework of the machine. In the rear end of the shaft 109 is a lever 110 which is connected by a pin and slot connection 111 with a lever 112 rotatably mounted on a stud 113 in the framework of the machine.

Pivoted on the lever 112 is a pendant 114, 125 having a slot 115 therein which controls a pin 116 mounted in one of the single key cams 117 of the single key mechanism, and said pendant has also a slot 118 which controls a pin 119 in the cam 120 of the single 130

key mechanism, it being understood that both the cams 120 and 117 are pivoted in the framework on shafts 121 and 122 respectively. The special fan 93 connected to the 5 key 71 is next to the extreme righthand fan of the actuator. When the pendant 114 is in the position shown in Fig. 2, the cams 117 and 120 are held together, and consequently the fan 93 cannot be operated, al- 10 though the two cams 117 and 120 may move together as a whole, thereby permitting the operation of any of the numeral keys, since the pendant 114 is pivoted on the lever 112. However, when the cam 106 engages the 15 roller 107 and thereby lowers the pendant 114 into the position shown in Fig. 3, the cams 117 and 120 are separated so as to allow the fan 93 to be operated. However, at this time none of the numeral keys can be 20 operated, since the cams of the single key mechanism allow but a single key to be operated at any time, and the fact of there being a space between the cams 117 and 120 will prevent any of the numeral keys 25 from being operated. The mechanism just described thus has the function of preventing the operation of the star printing key 71 in any space except the sub-units space of some particular totalizer, in this case the 30 totalizer 30, and at that point preventing the operation of any of the numeral keys.

In Fig. 8 I have shown my improved invention as applied to a vertical totalizer. In this case the totalizer containing the parts 35 corresponding to the lever 85, the latch 82, the comb 79, etc., have been identified by prime marks. Their functions will be readily understandable from a description of the same parts as present in the cross totalizer 32. In the event that it is desired 40 to make one of the vertical totalizers controlling as to the printing of a total, it is, of course, necessary to leave the parts corresponding to the lever 86, the latch 82, etc., out 45 of the cross totalizer 32.

Before using my improved device, it is, of course, necessary that the disc 50 be set so that one of the notches 51, 52 or 53 be in registry with the nose 56 before computation 50 is commenced. The alignment of the pointer 59 with the mark 60 will give an indication of whether this condition obtains. If not, the actuating mechanism may be very easily brought to this condition by simply operating 55 one numeral key a sufficient number of times to bring the pointer 59 into alignment with the mark 60. When this is done, the computation may then be commenced.

Many variations may be made from the 60 precise structure herein shown and described without departing from the spirit of my invention, since I claim:

1. In a calculating machine, the combination of an actuating mechanism, a totalizer, 65 a zero determining device located in said

totalizer, a function computing device located in said actuator, and means for printing a characteristic mark, said means being controlled by the joint action of said zero determining device and said function computing device. 70

2. In a calculating machine, the combination of a totalizer, an actuating mechanism, a zero determining device in said totalizer, a function computing device governed by 75 the condition of said actuator, and means controlled concurrently by the zero determining device and the function computing device for printing a characteristic mark indicative of the return of the totalizer to zero. 80

3. In a calculating machine, the combination of an actuating mechanism, a key, means for preventing the operation of said key unless said actuating mechanism has 85 been turned through a number of steps which are an integral multiple of 9, a totalizer adapted to be actuated by said actuating mechanism, and a control in said totalizer to prevent the complete operation of 90 said key unless said totalizer stands at zero.

4. In a calculating machine, the combination of a totalizer, an actuating mechanism adapted to insert numbers into said totalizer seriatim, a function computing device 95 governed by the condition of said actuator, a zero determining device in said totalizer, and means for printing a characteristic mark indicative of the return of said totalizer to zero, said printing means being controlled by the joint action of said zero determining device and said function computing device. 100

5. In a calculating machine, the combination of a set of numeral keys, actuating 105 mechanism operated by said numeral keys, a universal member in said actuating mechanism adapted to be operated upon the operation of any of said numeral keys, a function computing device associated with 110 said actuator, a special key also operative on said universal member, means to prevent the operation of said special key unless said function computing device stands at 9 or an integral multiple thereof, a totalizer, and 115 means associated with said totalizer to prevent the complete operation of said universal member by said special key unless said totalizer stands at zero.

6. In a calculating machine, the combination of a set of numeral keys, actuating mechanism operated by said numeral keys, a universal member in said actuating mechanism adapted to be operated upon the operation of any of said numeral keys, a 120 function computing device associated with said actuator, a special key for printing a characteristic mark, means to prevent the operation of said special key unless said function computing device stands at 9 or 125 130

an integral multiple thereof, a totalizer, and means associated with said totalizer to prevent the complete operation of said universal member by said special key unless 5 said totalizer stands at zero.

7. In a calculating machine, the combination of a traveling carriage, a series of numeral keys, a clearance proof key, and means controlled by said carriage at a predetermined point in its travel to lock said 10 numeral keys and to unlock said clearance proof key, said means normally maintaining said clearance proof key locked.

8. In a calculating machine, the combination of a carriage, a series of numeral keys, a clearance proof key, a series of devices actuated by said keys, a series of single-key cams permitting the operation of but one numeral key at a time and normally 15 locking said clearance proof key, and carriage controlled means acting on certain of said cams to unlock the clearance proof key and to lock the numeral keys.

9. In a calculating machine, the combination of a carriage, a plurality of column totalizers mounted on said carriage, a cross

totalizer, a clearance proof key for said cross totalizer, and means controlled by one of said column totalizers for controlling the operativeness of said clearance 30 proof key.

10. In a calculating machine, the combination of a carriage, a series of column totalizers, a cross totalizer, a normally inoperative clearance proof key for said cross 35 totalizer, and means associated with one of said column totalizers for making said key operative.

11. In a calculating machine, the combination of a carriage, a cross totalizer adapted for the calculation of numbers written in column positions determined by said carriage, clearance proof mechanism for said cross totalizer including a normally inoperative key, and a device traveling with 40 said carriage and acting to render said clearance proof key operative adjacent one 45 only of the column positions of said carriage.

In witness whereof I have hereunto subscribed my name.

ARTHUR F. POOLE.
